CLAIM

The ornamental design for a slide box, as shown and described.

DESCRIPTION

FIG. 1 is a rear perspective view of the slide box design in a closed position showing the left side thereof;

FIG. 2 is a right side view of the slide box of FIG. 1 in a closed position;

FIG. 3 is a top or bottom view of the slide box of FIG. 1 in a closed position, the two views being identical;

FIG. 4 is front view of the slide box of FIG. 1 in a closed position;

FIG. 5 is a rear perspective view of the slide box of FIG. 1 in a partially open position;

FIG. 6 is a rear perspective view of the slide box of FIG. 1 in an open position; and,

FIG. 7 is a front perspective view of the slide box of FIG. 1 in a partially open position.
